UNITED STATES PATENT OFFICE.

JOHN H. SWAN, OF CHICAGO, ILLINOIS, ASSIGNOR TO KLIPFEL MANUFACTURING CO.,
OF CHICAGO, ILLINOIS, A CORPORATION OF ILLINOIS.

VALVE-OPERATING MECHANISM.

1,157,059.

Specification of Letters Patent. Patented Oct. 19, 1915.

Application filed September 11, 1914. Serial No. 861,277.

To all whom it may concern:

Be it known that I, JOHN H. SWAN, a citizen of the United States of America, and a resident of Chicago, county of Cook, and State of Illinois, have invented certain new and useful Improvements in Valve-Operating Mechanisms, of which the following is a specification.

The main object of this invention is to 10 provide an improved form of instantaneous valve-operating mechanism for thermostats.

An illustrative embodiment of the invention is shown in the accompanying drawings, in which—

15 Figure 1 is a front elevation of a thermostat having the improved valve-operating mechanism, the expansion member being broken away so as to more clearly show the parts in the rear thereof. Fig. 2 is a longitudinal sectional elevation of the same. 20 Fig. 3 is a transverse sectional detail taken on the line A—A of Fig. 1. Fig. 4 is an enlarged transverse sectional detail taken on the line B—B of Fig. 1. Fig. 5 is a similar 25 view taken on the line C—C of Fig. 1.

In the construction shown in the drawings the several parts are supported on the frame 1 herein shown to be in the form of 30 two substantially cylindrical parts 2 and 3 connected by an integral web 4. The frame is suspended from a plate 5 by means of which the device is secured in position on the wall. The plate 5 also has the inlet and 35 outlet fluid pipes 6 and 7 connected thereto, the former leading from a source of fluid pressure (not shown) and the latter leading to a fluid motor (not shown) which is attached to the radiator valve. Air ducts or 40 passages 8 and 9 are formed in the parts 2 and 3 and connect respectively with the inlet and outlet pipes 6 and 7. The air passages 8 and 9 have communication with each other through the medium of a chamber 10, formed in the lower end of the frame 1, and in which 45 the controlling valve 11 operates.

The valve 11 as herein shown is in the form of a cylindrical disk carried on a stem 12 slidably mounted in the bushing 13 which has formed therein bleed openings or vents 50 14 providing communication between the chamber 10 and the atmosphere. The valve when in one position is adapted to shut off communication between the passages 8 and 9 and allow communication between the 55 passage 9 and the bleed openings 14, and when

in the other position is adapted to shut off communication between the passage 9 and the atmosphere and allow communication between the passages 8 and 9. The shifting of the valve from one to the other of these 60 positions is controlled by a lever 15 actuated by a fluid motor or diaphragm 16.

The diaphragm 16, which may be of any usual construction, is mounted near the upper end of the frame and the casing thereof 65 has a passage 17 leading therefrom to the passage 8. A cam 18 in the form of two cones arranged base to base is carried on the diaphragm 16, and engaged by a spring element carried by the lever 15.

The lever 15 is pivotally mounted at 19 on a post 20 supported on the frame 1. The lower end of the lever is bifurcated so as to engage the recessed head 21 carried on the valve stem 12. The spring element which 70 coacts with the cam 18 is formed from a wire extended through an aperture 22 in the lever and then bent U-shape so as to provide arms 23 extending up along the sides of the lever 15. Grooves are formed in the lever to receive the arms 23 and secure the same against dislodgment. The arms 23 extend beyond the end of the lever and constitute a fork 75 engaging the conical parts of the cam 18. Ears 24 are formed at the upper end of the 80 lever 15 which embrace the rods 23 and prevent them from becoming displaced when the crown of the cam 18 is being forced between them.

A clip 25 is slidably mounted on the lever 90 15 and embraces the rods 23. This clip is movable along the lever so as to adjust the tension of the arms 23 for the purpose of varying the sensitiveness thereof with respect to the movement of the diaphragm 16. 95

The actuation of the diaphragm is controlled by a thermostat member 26 formed in the usual manner of two metals having different coefficients of expansion. The member 26 is secured at its upper end to a lug 27 formed on the frame 1 and extends down along the frame and terminates adjacent to a stem 28. The stem 28 is secured to the frame 1 above the valve 11 and has a vent or bleed opening 29 extending therethrough and providing communication between the passage 17 and the atmosphere. The member 26 is provided with a gasket 30 secured thereto by means of a plate 31 which is adapted to be pressed against the end of 100 110

the stem 28, by movement of the member 26 through change in temperature, for the purpose of closing the bleed opening 29. A dial 32 is also secured to the stud 27, outwardly of the member 26, and carries a pointer 33 pivotally mounted thereon. The pointer 33 has a part 34 engaging the member 26 and is adapted to alter the tension thereof through the shifting of the pointer 33, as is customary in devices of this kind.

16 as is customary in devices of this kind.
A valve 35 is mounted on the plate 5 and
is arranged to control the flow of fluid from
the pipe 6 to the passage 8. Also a restrict-
ing valve 36 is mounted on the frame 1 and
15 suitably arranged to control the admission
of air to the branch passage connecting the
passages 8 and 17.

20 The operation of the device shown is as follows: The pointer 33 is set to register with a certain marking on the dial 32 which indicates the temperature that is desired. So long as the temperature is at or below such degree the thermostat member 26 is in its normal position and the bleed opening 25 29 is uncovered. The air pressure entering from the pipe 6 is therefore not effective upon the diaphragm 16, and the lever 15 is in the position shown in Fig. 2, so that the valve 11 is held in its depressed position for 30 closing the admission of air from the passage 8 into the chamber 10. With the several parts in these positions the passage 9 is open to the atmosphere through the bleed opening 14 and the motor (not shown) connected with the pipe 7 is allowed to exhaust to the atmosphere. A rise above the degree 35 for which the device is set in the temperature room, affects the thermostat 26 in the well known manner, and causes the lower 40 end thereof to move inwardly so as to press the gasket 30 over the end of the stem 28 and close the bleed opening 29. The air entering the passage 8 is therefore caused to flow up through the passage 17 into the diaphragm casing and urge the diaphragm outwardly. The cam 18 is thereby moved outwardly and the crown thereof is forced into the fork formed by the arms 23. The instant the crown of the cam 18 passes the 45 arms 23, the tension thereof causes them to move inwardly down the inclined face of the cam so that the lever 15 is shifted to elevate the valve 11. This movement of the valve 11 closes the bleed openings 14 and opens 50 communication between the passage 8 and the chamber 10 so that air is admitted to the motor passage 9 and causes the heat to be cut off. The parts remain in these positions 55 so long as the thermostat member 26 is held in a position to close the bleed opening 29. As soon as the temperature has fallen sufficiently to affect the thermostat member 26 and cause it to assume its normal position, the opening of the passage 29 releases the 60 pressure on the diaphragm 16 so that the 65 pressure on the diaphragm 16 so that the

cam 18 is shifted to its normal position as shown in Fig. 2. The lever 15 is thus actuated to shift the valve 11 to again close the admission of air from the passage 8 into the chamber 10 and open communication between the passage 9 and the bleed openings 14 so as to allow the exhaust from the motor. 70

Although but one specific embodiment of this invention has been herein shown and described, it will be understood that numerous details of the construction shown may be altered or omitted without departing from the spirit of this invention as defined by the following claims. 75

I claim:—

1. In a valve-operating mechanism, the combination of means having a passage for fluid therein, a valve controlling the flow of fluid through said passage, a fluid-controlled diaphragm, a cam and a spring element carried by said valve and diaphragm and co-acting with each other for causing the shifting of said valve through the actuation of said diaphragm, an adjustable device for regulating the tension of said spring, and means controlling the actuation of said diaphragm.

2. In a device of the class described, the combination of a valve and diaphragm associated with a quick-throw device comprising a cam and a lever, resilient arms for coacting with said cam, secured to said lever and extending parallel therewith, and a clip embracing said arms, slidably mounted on said lever for adjusting the resiliency of said arms with respect to said cam. 95 100

3. In a valve-operating mechanism, the combination of a frame having a fluid passage extending therethrough, a valve controlling the flow of fluid through said passage, a fluid-controlled diaphragm, a cam carried by said diaphragm, and comprising two conical portions arranged base to base, a lever connected to shift said valve, a spring rod extending transversely to the axis of said cam and carried by said lever and coacting with the conical portions of said cam to shift said valve through the actuation of said diaphragm, and means controlling the actuation of said diaphragm. 106 110 115

4. In a valve-operating mechanism, the combination of a frame having a fluid passage extending therethrough, a valve controlling the flow of fluid through said passage, a fluid-controlled diaphragm, a cam carried by said diaphragm, and comprising two conical portions arranged base to base, a lever connected to shift said valve, a resilient fork carried by said lever and coacting with the conical portions of said cam to shift said valve through the actuation of said diaphragm, and means controlling the actuation of said diaphragm. 125

5. In a valve-operating mechanism, the combination of a frame having a fluid pas- 130

5 sage extending therethrough, a valve controlling the flow of fluid through said passage, a fluid-controlled diaphragm, a cam carried by said diaphragm and comprising
 10 two cones arranged base to base, a lever pivotally mounted on said frame and connected to shift said valve, resilient arms secured to said lever and forming a fork yieldingly engaging said cones so as to actuate said lever by the shifting of said cam, and mechanism controlling the actuation of said diaphragm.

6. In a valve-operating mechanism, the combination of a frame having a fluid passage 15 extending therethrough, a valve controlling the flow of fluid through said passage, a fluid-controlled diaphragm, a cam carried by said diaphragm and comprising two cones arranged base to base, a lever pivotally mounted on said frame and connected to shift said valve, resilient arms secured to said lever and forming a fork yieldingly engaging said cones so as to actuate said lever by the shifting of said cam, and mechanism controlling the actuation of said diaphragm.

7. In a valve-operating mechanism, the combination of a frame having a fluid passage 20 extending therethrough, a valve controlling the flow of fluid through said passage, a fluid-controlled diaphragm, a cam carried by said diaphragm and comprising two cones arranged base to base, a lever pivotally mounted on said frame and connected to shift said valve, resilient arms secured to said lever and forming a fork yieldingly engaging said cones so as to actuate said lever by the shifting of said cam, means 25 for adjusting the resiliency of said fork, and mechanism controlling the actuation of said diaphragm.

8. In a valve-operating mechanism, the

combination of a frame having a fluid passage 45 extending therethrough, a valve controlling the flow of fluid through said passage, a fluid-controlled diaphragm, a cam carried by said diaphragm and comprising two cones arranged base to base, a lever pivotally mounted on said frame and connected to shift said valve, a resilient rod bent U-shaped secured to said lever at the transverse part thereof and having the arms thereof extending along the sides of the lever so that their outer ends form a fork 55 engaging said cones so as to actuate said lever by the shifting of said cam, said lever having grooves formed therein adapted to receive said arms and secure them against displacement, and means controlling the actuation of said diaphragm.

9. In a valve-operating mechanism, the combination of a frame having a fluid passage 60 extending therethrough, a valve controlling the flow of fluid through said passage, a fluid-controlled diaphragm, a cam carried by said diaphragm and comprising two cones arranged base to base, a lever pivotally mounted on said frame and connected to shift said valve, a resilient rod bent U-shaped secured to said lever at the transverse part thereof and having the arms thereof extending along the sides of the lever so that their outer ends form a fork 65 engaging said cones so as to actuate said lever by the shifting of said cam, a clip slidably mounted on said lever and embracing said arms and adapted to adjust the resiliency thereof, and means controlling the 70 actuation of said diaphragm.

Signed at Chicago this 31st day of August
 1914.
